United States Patent Office

Des. 188,896
Patented Sept. 27, 1960

188,896

CHAIR OR SIMILAR ARTICLE

Vincent Militano, Bethpage, N.Y., assignor to Finkel Outdoor Products, Inc., New York, N.Y., a corporation of New York

Filed July 2, 1959, Ser. No. 56,633

Term of patent 14 years

(Cl. D15—1)

Fig. 1.

Fig. 2.

Fig. 3.

Fig. 1 is a perspective view of a chair or similar article, embodying my new design;

Fig. 2 is a front elevational view of the frame of a chair or similar article embodying this design; and

Fig. 3 is an end elevational view of such back viewing the same from the direction indicated by the arrows 3—3 on Fig. 2.

The dominant features of my design reside in those portions shown in full lines in the drawings.

I claim:

The ornamental design for a chair or similar article, substantially as shown and described.
